UNITED STATES PATENT OFFICE.

EDGAR H. MOORE, OF CHICAGO, ILLINOIS, AND CHARLIE B. SURRETT, OF DRESDEN, TENNESSEE.

DISPENSING DEVICE.

Application filed September 4, 1926. Serial No. 133,635.

This invention relates to dispensing devices and more particularly to a device for dispensing granular substances, such as sugar, coffee or the like.

5 An important object of the invention is to provide a device of this character which, in operation, is capable of dispensing the proper bulk of the article to correspond to a selected payment and which is particularly 10 adapted for dispensing odd lots of the article, such, for example, as twenty-five or fifty cents' worth thereof, when the article is retailing at say six cents per pound.

A further and more specific object of the 15 invention is to provide a device of this character adjustable to compensate for variations in the price of the article which is being dispensed.

A still further object of the invention is 20 to provide a device of this character which may be readily and cheaply constructed, which will be durable and efficient in service and a general improvement in the art.

These and other objects we attain by the 25 construction shown in the accompanying drawings, wherein for the purpose of illustration is shown a preferred embodiment of our invention and wherein:—

Figure 1 is a front elevation partially 30 broken away of a dispensing device constructed in accordance with our invention;

Figure 2 is a side elevation thereof with portions of the casing broken away;

Figure 3 is a similar side elevation of the 35 opposite side;

Figure 4 is a section on the line 4—4 of Figure 1.

Referring now more particularly to the drawings, the numeral 10 generally designates a casing, the upper section of which is formed as a bin 11 for the reception of the article to be vended. At the lower end of the casing, an outlet spout 12 is provided for guiding the dispensed contents into a bag or other suitable receptacle. Connecting the outlet 13 of the hopper 11 and outlet spout 12 is a vertically extending dispensing spout 14, one wall 15 of which is movable to vary the capacity of the spout. In the present instance, the spout is shown as rectangular, three walls thereof being rigidly connected to one another to provide a substantially U-shaped trough, while the fourth wall slides between the spaced ends 55 of the two side walls 16 and is in the form

of a vertically extending block. U-shaped yokes 17 have the ends of the arms thereof secured to the side walls 16 and the cross bar 18 thereof opposed to the outer face of this block. Through these cross bars are directed set-screws 19, the inner ends of which engage the outer faces of the blocks and provide means for adjusting the blocks toward or away from the front wall 20 of the trough. The side face of the block 15 is provided with vertically extending lines 21 which, by their coaction with the edge of one of the walls 16, provide a guide for determining the depth to which the block 15 is projected between the arms 14. Associated with these lines are suitable indicia 22 corresponding to the cost price per pound of the substance being vended. If the cost of the article is six cents per pound, a line having the indicia 6 adjacent thereto is 70 aligned with the edge of the associated wall 16 in order that the dispensing spout may have the proper cross sectional area. The front wall 20 is provided with vertically spaced slots 26 through which are slidable 75 slide valves 27, 27', the edges of which are guided by grooves 28 formed in adjacent faces of the side walls 16. The lowermost slide valve 27' is arranged immediately above the upper end of the outlet spout 12 and has 80 secured thereto an operating handle 29 extending directly through the front wall of the casing 10. The remaining slides 27 each have pivotally secured thereto one end of a lever 30, the opposite end of which has 85 pivotally connected thereto a push rod 31 which projects through the front wall of the casing and is provided with a button head 32 which serves both as a means for operating the rod and as an indicia support. 90

Through these rods, the slide valves 27 may be either completely withdrawn or advanced, so that they do not in any way obstruct the dispensing spout 14 or so that they completely obstruct the same without 95 regard to the position of the rear wall. The front faces of buttons 32 bear indicia 33 corresponding to given sums of money, as five, ten, fifteen, etc., and the valves associated therewith are properly spaced so that 100 they cut off a column of the substance which is being dispensed of the proper height for the given value represented by the indicia. If, for example, sugar is selling for five cents 105 a pound and the rear wall is properly 110

adjusted, the valve associated with the button bearing the indicia 10, when moved inwardly into engagement with the rear wall, will cut off between itself and the valve actuated by the handle 29 a column of sugar within the dispensing spout 14, which contains two pounds of sugar, whereas if the sugar is selling at six cents a pound and the wall is properly adjusted, it will cut off but one and ¹⁰ two-thirds pounds of sugar.

The levers 30 are preferably mounted upon a single vertically extending pivot shaft 34, spacers 35 being disposed between adjacent levers to maintain them in properly spaced ¹⁵ relation.

In operation, it will, of course, be understood that the lower valve 27' is normally forced inwardly by its handle until it engages the rear wall and the remaining valves ²⁰ are all withdrawn, so that they do not obstruct the spout 14. If a person asks for fifteen cents' worth of sugar, the button bearing the indicia 50 is engaged with the fingers and shifted outwardly until the ²⁵ valve associated therewith comes into engagement with the wall 15. A bag is then placed in position at the outlet spout and the lowermost valve 27' opened through its handle 29, permitting the substance to pass ³⁰ out through the outlet spout to the bag. When the substance below the actuated valve has been removed, the lowermost valve is again closed and the valve, whose operating ³⁵ button bears the indicia 50, again shifted to its open position.

It will be obvious that by the use of an apparatus of this character, a grocer is enabled to dispense substances in odd lots without the necessity of troublesome and time ⁴⁰ consuming calculations to determine what the proper amount of the substance may be at the present price per pound.

Since the construction hereinbefore set forth is capable of a certain range of change and modification without materially departing from the spirit of the invention, we do not limit ourselves to such specific structure except as hereinafter claimed. ⁴⁵

We claim:—

In combination, a receptacle, an outlet ⁵⁰ spout therefor spaced from the receptacle, a dispensing spout connecting the receptacle and the outlet spout and adapted to contain a column of the substance to be vended, said dispensing spout having a movable wall ⁵⁵ adjustable to determine the cross sectional area of the column within the dispensing spout whereby the column of the substance within the dispensing spout may be regulated to have a predetermined value at varying costs ⁶⁰ per pound, a valve normally closing communication between the outlet spout and the lower end of the dispensing spout, the wall of the dispensing spout opposing the movable wall thereof having slots, valves slideable through said slots for engagement with the movable wall in any of said positions to thereby cut off the column of the substance lying therebelow from the receptacle and the remainder of the dispensing spout, a casing ⁷⁰ surrounding said dispensing spout and valves, a vertical shaft within said casing, a lever connected at one end to each valve and at its center to a shaft and an operating rod connected with the opposite end of each ⁷⁵ lever projecting through the wall of the casing the outer end of each operating rod having means associated therewith indicating the value of the portion of the column cut off by operation of the valve. ⁸⁰

In testimony whereof we hereunto affix our signatures:

EDGAR H. MOORE.
CHARLIE B. SURRATT.
